(57) **CLAIM**

The ornamental design for a sensor attaching article as shown and described.

DESCRIPTION

FIG. 1 is a front, right-side, bottom perspective view of a first embodiment of a sensor attaching article, showing the new design;

FIG. 2 is a front elevational view thereof;

FIG. 3 is a rear elevational view thereof;

FIG. 4 is a right-side elevational view thereof, the left-side elevational view thereof (not provided) being a mirror image thereof;

FIG. 5 is a top plan view thereof;

FIG. 6 is a bottom plan view thereof;

FIG. 7 is a cross-sectional view taken along line 7-7 in FIG. 5;

FIG. 8 is a rear, right-side, top perspective view thereof; and FIG. 9 is a perspective view showing the sensor attaching article in a state of use.

FIG. 10 is a front, right-side, top perspective view of a second embodiment of a sensor attaching article, showing the new design;

FIG. 11 is a front elevational view thereof;

FIG. 12 is a rear elevational view thereof;

FIG. 13 is a right-side elevational view thereof, the left-side elevational view thereof (not provided) being a mirror image thereof;

FIG. 14 is a top plan view thereof;

FIG. 15 is a bottom plan view thereof;

FIG. 16 is a cross-sectional view taken along line 16-16 in FIG. 14;

FIG. 17 is a rear, right-side, top perspective view thereof; and,

FIG. 18 is a perspective view showing the sensor attaching article in a state of use.

The broken lines depict environment that form no part of the claimed design.
